UNITED STATES PATENT OFFICE.

MORLEY PUNSHON REYNOLDS, OF CLEVELAND, OHIO, ASSIGNOR TO THE W. S. TYLER COMPANY, OF CLEVELAND, OHIO, A CORPORATION OF OHIO.

HATCH-VENTILATOR AND ICE-PLUG.

1,274,197.

Specification of Letters Patent. Patented July 30, 1918.

Application filed April 25, 1916, Serial No. 93,418. Renewed June 8, 1918. Serial No. 238,960.

To all whom it may concern:

Be it known that I, MORLEY PUNSHON REYNOLDS, a citizen of the United States, and resident of Cleveland, in the county of 5 Cuyahoga and State of Ohio, have invented a new and useful Improvement in Hatch-Ventilators and Ice-Plugs; and I do hereby declare the following to be a full, clear, and exact description thereof.

10 My invention pertains to hatch ventilators and ice plugs, particularly for use in connection with railroad refrigerator cars, produce cars or the like; and the invention relates especially to combined hatch ventilators and 15 ice plugs for such cars. It is an object of my invention to provide a hatch ventilator for produce cars and the like, which will permit the admission to the car of a greater volume of air than has been the case with 20 the ventilators commonly in use. It is a further object of my invention to provide a hatch ventilator which, while admitting air to the car in large quantity, will effectually exclude cinders or other dirt. It is another 25 object of my invention to provide a hatch ventilator which, while performing its ventilating functions properly, will effectively exclude rain and other moisture, from the interior of the car. Another object of my 30 invention lies in the provision of a combined ventilator and ice-plug in which the ventilator and ice-plug may be opened together, or the ice-plug may be opened alone, at will. It is still another object of my invention to 35 provide a combined ventilator and ice-plug of a strong, simple and economical construction, which will be convenient in use and unlikely to get out of order and the parts of which may readily be repaired in case of accident, and to improve upon hatch-ventilator 40 and ice-plug constructions generally. And other and further objects of the invention will appear from the following specification taken in connection with the claims annexed thereto.

A combined ventilator and ice-plug embodying my invention is shown, as an example, in the accompanying drawings and described in the following specification. It 45 will be understood, however, that my invention may take other forms, and that alterations may be made in the particular form which has been described and shown, without exceeding the scope of the invention, as 55 defined in the appended claims.

In the drawings:

Figure 1 is a sectional side elevation of the ventilator, showing, in full lines, the ventilator and ice-plug closed, and, in broken lines, the ice-plug open, the section 60 being taken on the line 2—2 of Fig. 2, looking in the direction of the arrows;

Fig. 2 is a section taken on the line 3—3 of Fig. 1, looking in the direction of the arrows;

Fig. 3 is a partial end view of a car having hatch-ventilators constructed in accordance with my invention applied thereto.

Like characters of reference indicate like parts throughout the following specification 70 and the several figures of the accompanying drawings.

Referring now to the drawings, 10 designates a coaming, preferably of wood, of rectangular shape, which is built on the car- 75 roof around each of the hatch-openings, of which latter, in the form illustrated, there are four, one at each side of each end of the car.

The coaming 10 is provided with a lining 80 11 having therein a downwardly and inwardly tapered opening 12 communicating with the interior of the car. Secured to the coaming is a cap, formed of bent sheet-metal, which includes a ledge 13, lying on 85 top of the coaming, a flange 14 which closely embraces the upper part of the outside of the coaming, and a seat-portion 15 which extends down into the tapered opening 12 of the lining 11 and lies flush with the surface 90 thereof. Between the ledge 13 and the seat-portion 15, the cap is formed with an upwardly-extending bead 16 extending entirely therearound.

The ventilator includes a box-shaped hood 95 17, the open lower side of which rests upon the cap-ledge 13, outside and surrounding the bead 16. Embracing the outer or rear end and two sides of the hood 17, is a strap 18 which terminates in ears or lugs 19. 100 These lugs are hingedly mounted on a transverse rod 20, which latter is carried by two pairs of brackets 21 secured to the cap-flange 14 at the front end thereof,—i. e. the end which faces away from the end of the car. 105 Thus the ventilator hood may be swung, about the rod 20, up and away from the hatchway; and, to facilitate this, the hood is provided with a lifting handle 22 at the top thereof. At the end of the device oppo- 110

site to the rod 20, the strap 18 is provided at its center with a staple 23, and the cap-flange 14 has hinged thereto a hasp 24 which may be passed over the staple 23. When 5 the ventilator hood is closed down with the hasp in place on the staple, a padlock may be passed through the latter to lock the ventilator in its closed condition, or a car-seal or the like may be employed for the same 10 purpose.

The front end of the ventilator hood—*i. e.*, the end facing away from the adjacent end of the car—is open, and has secured therein a screen 25, the latter being held 15 in place by means of suitable clamping frames extending around the same. This screen prevents the entrance of dirt, cinders, and the like into the car. Secured to the side walls of the hood, and extending trans- 20 versely there-across immediately behind the screen 25, are a series of superposed, downwardly and rearwardly inclined baffle plates 26, the lower ones of which are of less width than the upper ones. Extending from 25 immediately behind the screen 25, at the lower part thereof to a point near the middle of the hood, is a large downwardly and forwardly inclined draining baffle 27, which traverses the hood from one side of the 30 same to the other. Located adjacent the center of the draining baffle 27 is a baffle 27^a which is inclined downwardly and forwardly at a considerably steeper angle than that of the draining baffle 27. The baffle 35 27^a also extends across the hood. Located at the rear of the baffle 27^a is a narrow baffle 28 which is downwardly and rearwardly inclined, and extends across the hood immediately beneath the top of the 40 latter. At the rear end of the hood, a transversely-extending curved plate 29 is secured to the top and rear wall of the hood.

When a car is traveling at high speed through the rain, the latter tends to blow 45 directly, and almost horizontally, into the mouth of the hood. Any rain thus entering the hood strikes the baffles 26, and is deflected thereby downward against the draining baffle 27. Any moisture which may be 50 carried farther, by reason of the strong rush of air into the hood, strikes the baffle 27^a and is thereby deflected upward against the baffle 28, wherefrom it drops again onto the upper part of the draining baffle 27. 55 Thus all the moisture is directed onto the draining baffle 27, from which it drains onto the ledge 13, and thence off upon the roof of the car. The curved plate 29 directs downward, through the hatch-way, the currents 60 of air which are directed by the baffle plates upward against the top of the hood.

The ice-plug includes a plug-portion 30 of a size and shape to fit snugly in the tapered opening 12 and rest upon the seat- 65 ing-portion 15 of the cap. The plug por-

tion 30 is formed of suitable heat-insulating materials and is provided with a pair of bearings 31 secured to its upper face. Hinged arms 32 have their forward ends hingedly connected with the bearings 31, 70 and their rear ends rockably mounted on the rod 20 supported in the brackets 21. Thus the plug portion may be swung, by means of the hinge arms 32, up out of engagement with the opening 12. This swing- 75 ing movement may be effected either together with the ventilator hood (both parts hinging about the same axis), or independ- ently thereof.

To permit of the opening and closing of 80 the ice-plug independently of the ventilator hood, the plug-portion 30 is provided, at its rear end, with a stirrup 33, in which engages the end 34 of a crank arm 35, which latter forms part of a stud 37 which extends 85 through the rear wall of the ventilator hood and is rotatably mounted in the same, such wall being reinforced by a plate 36 at the point where the stud passes therethrough. The stud 37 has secured thereto, outside the 90 hood, a handle 38, by means of which the crank arm 35 may be rotated in one direction or the other. With the parts in the position shown in full lines in Fig. 2, it will be seen that if the crank arm 35 is 95 rotated in a clockwise direction its end 34 will engage the stirrup 33 and thereby raise the plug portion 30 into the position shown in broken lines in the figure. Rotating the crank arm in the opposite direction will, 100 of course, permit the plug-portion to resume its seating position in the opening 12.

The handle 38 has extending inwardly therefrom a hasp 39 which is adapted to pass over a staple 40, secured to the rear 105 wall of the hood, when the handle 38 is in the position in which the plug-portion 30 is closed. When the handle 38 is in the position in which the plug-portion 30 is open, the hasp 39 coöperates with a staple 110 41, which is likewise secured to the rear wall of the ventilator hood. By means of padlocks, car-seals, or the like, the hasp 39 may be locked to either one of the staples 40 and 41, and the plug-portion 30 thereby 115 locked in either its open or closed position.

In use, two of the devices are usually provided at each end of the car, one on each side of the center thereof. Each of the devices is disposed with its open part facing 120 toward the center of the car. Thus the device at the rear end of the car will take in air (when the plug-portion is open), and suction will be created in the device at the front end of the car, thereby assisting in 125 drawing out the air at that point. The intake ventilators, being placed at the rear end of the car, where the rush of air along the roof is greatest, have a maximum efficiency in operation. Cinders and other 130

dirt are caught by the screen 25 and thus prevented from reaching the interior of the car. Likewise, rain is caught by the baffles 26, 27, 27^a and 28 and permitted to drain off 5 onto the roof instead of reaching the interior.

When the device is to be used for ventilating purposes solely, the plug-portion 30 is opened by means of the handle 38, the ventilator hood remaining closed. When the device is to be used for refrigeration, the ventilator hood 17 and plug-portion 30 may be raised together, to permit of ice being placed into the bunker. When the ventilator hood 17 and plug-portion 30 are thus simultaneously raised, the plug-portion 30 may be either in the position, relatively to the hood, shown in Fig. 1, or it may be in the position relatively to the hood, shown in the dotted 10 lines of Fig. 2; in the latter position, the plug is out of the way, and does not interfere with icing, etc. The plug-portion can likewise be closed with the ventilator hood, as a unit. It will be seen that the device is 15 very easily changed from the requisite position for icing to the requisite position for ventilation, and that it may be readily locked or sealed in any one of its positions. The device is of simple construction and there 20 are no parts which are liable to get out of order during use. The construction is such that, in case of accident, any damaged parts 25 may readily be repaired.

Having thus fully described my invention 30 what I claim as new, and desire to secure by Letters Patent, is:

1. The combination with a car having a hatch-opening in the roof thereof, of a ventilator associated with said hatch-opening and 40 covering the same, said ventilator including a hood portion having an opening at the forward end thereof, a plurality of downwardly and rearwardly inclined baffles in said opening, a downwardly and forwardly 45 inclined baffle mounted in said hood portion directed toward the opening, and a downwardly and rearwardly inclined baffle at the end of said hood remote from said opening, thereby to deflect the air currents downward 50 through said hatch-opening.

2. The combination with a car having a hatch-opening in the roof thereof, of a venti-

lator associated with said hatch-opening and covering the same, said ventilator including a hood portion having an opening 55 at the forward end thereof, a plurality of downwardly and rearwardly inclined baffles in said opening, a downwardly and forwardly inclined baffle mounted in said hood portion directed toward the opening thereof, a downwardly and rearwardly inclined baffle at the end of said hood remote from said opening, thereby to deflect the air currents downward through the hatch-opening, and a screen 60 mounted in the opening of said hood portion. 65

3. The combination with a car having a hatch-opening in the roof thereof of a ventilator associated with said hatch-opening and covering the same, said ventilator including a hood portion having an opening at the forward end thereof, a plurality of downwardly and rearwardly inclined baffles mounted in said opening, a downwardly and forwardly 70 inclined baffle mounted in said hood portion directed toward the opening thereof, a downwardly and rearwardly inclined baffle at the end of the said hood remote from said opening, thereby to deflect the air currents downward 75 through the hatch-opening, and means, adjacent to the opening of said hood, for hingedly connecting said hood with the car roof. 80

4. The combination with a car having a 85 hatch-opening in the roof toward one end thereof, of a ventilator associated with said hatch-opening and including a hood hingedly mounted with respect to the roof of the car and having an opening directed away 90 from the end of the latter, a plurality of downwardly and rearwardly inclined baffles mounted in said hood adjacent said opening, and a downwardly and forwardly inclined baffle below said plurality of baffles for collecting moisture from said first-named baffles and directing it to said hood-opening. 95

In testimony whereof, I the said MORLEY PUNSHON REYNOLDS, have hereunto set my hand.

MORLEY PUNSHON REYNOLDS.
